CLAIM

The ornamental design for a gaming machine, as shown and described.

DESCRIPTION

FIG. 1 is a front perspective view of a gaming machine showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view thereof, shown without the housing for ease of illustration, shown in enlarged scale; and,

FIG. 9 is a top plan view thereof, shown without the housing for ease of illustration, shown in enlarged scale.

The broken lines shown in the drawings are included for the purpose of illustrating portions of the gaming machine that form no part of the claimed design. The claimed design is directed to the edges of the buttons, the edges of the display, and the edges of the button deck, as shown in the drawings.
